UNITED STATES PATENT OFFICE.

DARWIN HANAUER, OF LA GRANGE, ILLINOIS, ASSIGNOR TO KINNEY-ROME COMPANY, OF CHICAGO, ILLINOIS, A CORPORATION.

COLLAPSIBLE BED.

Application filed January 25, 1922. Serial No. 531,585.

My invention has reference more particularly to a bed structure comprising two sections, which may be nested, one within the other to form a single bed or davenport, or may be extended to afford a double bed, or completely separated, thus forming twin beds.

Beds of this type heretofore have had the movable section arranged to slide under the mattress supporting surface, or spring frame of the stationary section, and as the mattress was usually doubled over on the stationary section toward the side from which the movable section is withdrawn, it was necessary to lift the entire mattress in order to fold or unfold same. Moreover a flounce or drape is usually provided on the mattress to hang down along the ends and outer side of the collapsed bed, and in previous structures this was in the way and liable to become caught in the moving parts and had to be straightened out each time the bed was extended or collapsed. It has also been the previous practice to provide supporting legs for the movable section only at the outer side, the inner side being slidably mounted on the stationary section.

In my construction the upper section is movable so that the doubled over mattress is pulled out with this section, and it is merely necessary to lay the top fold of the mattress back over the stationary section in extending the bed, and vice versa in collapsing the structure, thus avoiding the necessity of lifting the entire mattress as in previous bed structures of a similar character. Moreover as the flounce is attached to the lower fold of the mattress which latter moves with the movable section, the flounce is not disturbed by the extending or collapsing of the bed structure, nor by the folding and unfolding of the mattress, and there is also no danger of the flounce becoming caught in the moving parts.

Another important feature of my construction is that neither of my sections depend upon the other for support, but each is constructed in the form of a complete self-supporting cot which interlocks with the other to form the extensible bed but may be readily separated and used independently as a separate cot.

Other features or objects of my invention have to do with facilities for insuring direct in and out movement of the movable section

so that the latter may be grasped at any point and easily adjusted without danger of cramping or binding between the sections, and there are also other features of improvement embodied in my invention which will appear from the following detailed description thereof.

On the drawings:

Fig. 1 is a top view of the movable section of a collapsible bed embodying my improvements;

Figs. 2 and 3, side and end views respectively of said section;

Fig. 4, a fragmentary view of a modified construction for the end of said section;

Fig. 5, a top view of the stationary section of the bed;

Figs. 6 and 7, side and end views respectively of said stationary section;

Fig. 8, an end view of the device showing the manner of assembling the two sections;

Fig. 9, a transverse sectional view of the bed opened out and having the mattress placed in position ready for use;

Fig. 10, an enlarged fragmentary view of adjoining end portions of the two bed sections showing the manner in which one is nested within the other;

Fig. 11, a sectional view on the line 11—11 of Fig. 10;

Fig. 12, a view on the line 12—12 of Fig. 10;

Figs. 13 and 14, front and side views respectively showing the manner of mounting the rollers on the movable section; and

Fig. 15, a section view on the line 15—15 of Fig. 14.

Referring to the drawings, the reference numerals 1 and 2 indicate, as a whole, the stationary and movable sections respectively of the bed, each of which is composed of a pair of spaced end frames having the corresponding legs 3 connected by a side rail 4 and brace rod or bar 5. Each end frame is preferably constructed of a length of angle iron which has the end portions thereof bent at right angles to the intermediate portions 6 to form the legs 3, one flange of the angle iron being notched at the juncture of the legs 3 with the intermediate portion 6 to effect the bend and afford a mitre fit. A corner brace 7 connects each leg with the intermediate portions 6 as shown.

The side rails 4 which are preferably of angle iron are positioned a sufficient dis-

tance below the upper ends of the legs 3 so as to afford ample clearance below the spring structure 8 which extends between the intermediate or top portions 6 of the 5 end frames and there are corner braces 9 between the side rails and legs 3 as shown. The spring structure 8 which supports the mattress is preferably of woven or link wire fabric and has a number of helicals 10 at 10 each end connected with the top portion 6 of the corresponding end frame to hold the spring structure under the required tension, and in order to brace the end frames against the strain of the spring structure and the 15 supported weight, the brace rods or bars 5 are positioned well below the side rails 4, substantially as shown.

The section 1 of the bed is sufficiently smaller in length and height to nest within 20 the section 2 and is combined therewith by inserting the legs 3 at one side of the section 1 between the spring structure 8 and side rail 4 of the section 2 as shown in Fig. 8, so that the sections are adjustable for extending and collapsing the bed, and are interlocked so as to prevent separation thereof when the bed is extended.

The section 1 which remains stationary is preferably provided with knobs 11 instead of casters on the lower ends of the 30 legs 3 so that it will not move easily. The other section 2 is preferably mounted on bed ends 12 which serve to enhance the appearance of the bed and afford arm rests 35 when the structure is collapsed to couch or davenport form. The marginal frame of these bed ends comprises side posts 13 which correspond to the legs 3 of the section 2 and are secured to the latter by bolts 14 or other 40 suitable fastenings and project below said legs so as to support the section 2 at the proper elevation. This construction renders it possible to convert the section 2 into an ordinary cot by merely removing the bed 45 ends 12, or a standard cot structure may be utilized in making the bed by merely attaching the bed ends 12 thereto. The posts 13 are supported by rollers 15 which do not have a caster mounting but are held in a 50 fixed position in line with the required direction of movement of the section 2 or their axes of rotation remain always parallel with the length direction of the bed so that they serve to effectivly guide the movement of 55 this section and avoid cramping or binding which occurs when the usual caster wheels are employed. These wheels or rollers 15 may be mounted on the posts 13 in any suitable manner, as for example as shown in 60 Figs. 13, 14 and 15, wherein the yoke 16 has the wheel or roller 15 journaled on a stem or pin 17 which extends between and connects the arms of the yoke and the intermediate portion of the yoke is inserted into 65 the lower end of the post 13 and secured

therein by the rivet 18 or other suitable fastening.

It is not necessary to use any bed ends or arm rests on the section 2 as the latter may, if desired, have the legs 3 long enough to 70 support the spring structure 8 at the required elevation and the rollers 15 mounted directly on the lower ends of the legs 3. Arm rests can be provided on this structure as shown at 19 in Fig. 4 wherein a short 75 frame is secured to the upper ends of the legs 3.

For the purpose of further insuring the necessary direct in and out movement of the section 2, I have provided a pair of 80 guide straps 20 and 21 at each end of the section 2, and between which the legs 3 of the section 1 are confined. These guide straps extend between the side rails 4 of the section 2 and the former may be permanently 85 attached to the side rails. The guide strap 21, however, is preferably pivoted to the upper flange of the inner side rail 4, as indicated at 22, so that when the outer end is released it may be swung as indicated by the 90 dotted lines 23 to a position directly over the side rail 4, thereby rendering it possible to disconnect or separate the sections 1 and 2 without difficulty when it is desired to use them separately as individual cots. To this 95 end the outer ends of the guide straps 21 are preferably secured to the side rail 4 by bolts 24 or other detachable fastenings, so that these guide straps may be swung out of the way whenever the occasion may require.

A mattress 25 of suitable width to extend over both sections 1 and 2 when the latter are opened out to the full width is provided, and when the bed structure is contracted or collapsed, the portion of the mattress lying over the section 1 is merely folded over on top of the portion of the section 2, as indicated by dotted lines at 26 in Fig. 9. This mattress preferably has a flounce or drape 27 which hangs down along the outer side of the section 2, and there may also be end portions 28 of the flounce or drape preferably separate from the portion 27 so as to fit down between the section 2 and the bed end 12 thereon. With this construction it will be observed that the lifting of the mattress in collapsing or extending the bed is not only avoided as it is merely necessary to fold half of the mattress to the position shown by dotted lines at 26, or to the position shown 110 in full lines, but moreover as the flounce or drape extends down around the movable section 2 it is not in any way disturbed in opening or closing the bed and there is no possibility that it may become caught in moving parts, as in bed structures of this character 115 which have been provided heretofore.

The bed end 12 at one end of the section 2 may serve as a pillow rest and to provide a 120 pillow rest for the other section 1 a wire 125

frame 29 is pivoted to the top portion 6 of the end frame of said section, so that it may be adjusted to the position shown by dotted lines in Fig. 6 or laid down on to the upper 5 surface of the spring structure 8, as shown by full lines.

After a bed has been used for some time the spring tension on the spring structure 8 some times becomes relaxed and as the 10 spring structure 8 of the section 1 slides under the spring structure 8 of the section 2 in rather close proximity thereto, it is possible that the spring structure of the section 2 might sag sufficiently to catch on the 15 spring structure of the section 1. To avoid contact between the spring structures and facilitate the sliding relative movement thereof, a pair of straps 30 are extended across under the spring structure 8 of the 20 bed section 2 at suitable intervals and have the outer ends connected to opposite sides of the spring structure 8 so as to serve as guides which slide over the upper surface of the springs 8 on the section 1.

25 With the construction as above described, having the rollers on the movable section arranged to confine the movement of the latter to a direct in and out movement, and also having the guide straps 20 and 21, it is not 30 necessary to grasp the section 2 intermediate of the ends for operating same so as to avoid binding as in previous structures, but the section may be readily operated without binding by applying the required pressure at 35 the ends of the section or any other point.

In the description of my invention and particularly in the following claims, I use the terms stationary and movable to distinguish the sections,—not intending, of 40 course, that the one section is incapable of movement, but to signify that the so-called movable section is the one which is designed and intended to be moved or adjusted in extending or collapsing the bed structure and 45 that the so-called stationary section is designed and intended to remain stationary while the other section is adjusted.

While I have shown and described my invention in a preferred form, I am aware that 50 various changes and modifications may be made without departing from the principles of my invention, the scope of which should be determined by reference to the following claims.

55 I claim as my invention:

1. A metallic couch bed comprising inner and outer, self-supporting, telescoping sections, separable into independent beds and each comprising angle bar end frames forming end bars and corner legs, a metallic fabric connecting the end bars, and side bars spaced below the fabric and connecting the corner legs, the outer section having pairs of guide bars connecting the end portions of 60 the side bars thereof, said sections being

adapted to be nested with each leg at one side of the inner section extending over one of the side bars of the outer section and between one pair of guide bars thereof, substantially as described.

2. A metallic couch bed comprising inner and outer, self-supporting, telescoping sections, separable into independent beds and each comprising angle bar end frames forming end bars and corner legs, a metallic fabric connecting the end bars and side bars spaced below the fabric and connecting the corner legs, the outer section having pairs of guide bars connecting the end portions of the side bars thereof, said sections being adapted to be nested with each leg at one side of the inner section extending over one of the side bars of the outer section and between one pair of guide bars thereof, the lower ends of the legs of the inner section being adapted to frictionally engage the supporting surface and the legs of the outer section being provided with rollers having fixed axes disposed lengthwise of the section, substantially as described.

3. A metallic couch bed comprising inner and outer, self-supporting, telescoping sections, separable into independent beds and each comprising angle bar end frames forming end bars and corner legs, a metallic fabric connecting the end bars and side bars spaced below the fabric and connecting the corner legs, the outer section having pairs of guide bars connecting the end portions of the side bars thereof, said sections being adapted to be nested with each leg at one side of the inner section extending over one of the side bars of the outer section and between one pair of guide bars thereof, and the end frames of said sections having diagonal braces extending between the legs and end bars thereof, the diagonal braces at opposite sides of the inner section extending over the opposite side bars of the outer section in the nested and extended positions respectively of the sections.

4. In a bed of the class described, the combination of a stationary section, a movable section adjustable to and from the stationary section and adapted to nest the latter in the former or form a lateral extension thereof, supporting legs at the ends of the sections, a longitudinal brace at each side of and extending between the ends of one of the sections and a pair of parallel guides at each end of one of the sections extending between and secured at their ends to the aforesaid longitudinal braces and embracing a leg of the other section so as to restrict the movement of the movable section to a direction at right angles to the stationary section.

5. In a bed of the class described, the combination of two bed sections, each having a pair of inverted U-shaped end frames hav-

ing the corresponding legs thereof connected by longitudinal braces and having a resilient bed bottom stretched between the upper portions of the end frames, said frames being interengaged at their sides to permit movement of one section laterally to and from the other section and to limit the relative lateral movement of the sections, a pair of guides at each end of one of the sections 10 extending between and having the ends secured to the longitudinal braces of said section and embracing a leg of the other section therebetween, the inner guide of each pair being extended over a longitudinal brace of 15 the other section so as to lock the sections together and said guide being removable to permit separation of the sections.

6. In a collapsible bed, a stationary section, a movable section adjustable to and 20 from the stationary section and adapted to nest the latter within the former or form

a lateral extension thereof, said sections having side and end rails, a pair of parallel guides at the end of the stationary section, the inner guides being pivoted to swing in line with the side rail of the section, and legs on the movable section slidable between the guides. 25

7. In a collapsible bed, a stationary section, a movable section adjustable to and 30 from the stationary section to nest the latter in the former or form a lateral extension thereof, a pair of guides mounted across each end of one of the sections and between which an end portion of the other section 35 moves for confining the movement of the movable section to a direction directly to and from the side of the stationary section, one of said guides being displaceable to permit separation of one section with respect 40 to the other. 35

DARWIN HANAUER, M. E.
